United States Patent

Des. 238,705

Patented Feb. 3, 1976

238,705

CAMERA

Ronald Emmerling, New City, N.Y., assignor to
Berkey Photo, Inc., New York, N.Y.

Filed May 3, 1974, Ser. No. 466,735

Term of patent 14 years

Int. Cl. D16—01

U.S. Cl. D61—1 B

FIG. 1

FIG. 2

FIG. 3

FIG. 4

FIG. 5

FIG. 6

FIG. 7

FIG. 1 is a front elevational view of a camera with the self-contained strobe light assembly in an inoperative condition, showing my new design;

FIG. 2 is a right side elevational view thereof;

FIG. 3 is a left side elevational view thereof;

FIG. 4 is a rear elevational view thereof;

FIG. 5 is a top plan view thereof;

FIG. 6 is a front elevational view of the camera shown in FIG. 1 with the strobe light assembly in an operative condition; and

FIG. 7 is a right side elevational view of FIG. 6.

I claim:

The ornamental design for a camera, substantially as shown and described.
